DESIGN FOR A NOVELTY SWORD

Nathan Joseph Leigh, Great Neck, N. Y.

Application May 28, 1942, Serial No. 107,033

Term of patent 3½ years

To all whom it may concern:

Be it known that I, Nathan Joseph Leigh, a citizen of the United States and a resident of Great Neck, county of Nassau, State of New York, have invented a new, original, and ornamental Design for a Novelty Sword, of which the following is a specification, reference being had to the accompanying drawing, forming part thereof.

I claim:

The ornamental design for a novelty sword, substantially as shown.

NATHAN JOSEPH LEIGH.
